Primary Examiner — John A Voytek(74) *Attorney, Agent, or Firm* — June E. Rickey; Robert N. Lipcsik(57) **CLAIM**

The ornamental design for a tire, as shown and described.

DESCRIPTION

FIG. 1 is a perspective view of a tire taken generally from the front and a first side of the tire;

FIG. 2 is a front view thereof;

FIG. 3 is a right side view thereof; the left side view being identical thereto;

FIG. 4 is an enlarged partial, perspective view of the taken along Line 4 of FIG. 1 thereof;

FIG. 5 is an enlarged, partial front view taken along Line 5-5 of FIG. 2 thereof; and,

FIG. 6 is an enlarged, partial side view taken along Line 6 of FIG. 3 thereof.

The broken lines and the region between the broken lines defining the inner bead and the first or second sidewall depict subject matter that forms no part of the claimed tire, and is included for the purpose of illustrating the full tire. Likewise, the tire interior forms no part of the claim. The tread pattern is understood to repeat throughout the circumference of the tire. The other side view is identical to the illustrated side view.

The dashed broken lines indicating an enlargement portion of the design form no part of the claimed design.
